(57) **CLAIM**

The ornamental design for a headrest for automobile, as shown and described.

DESCRIPTION

FIG. 1 is a front, right, and top perspective view of a headrest for automobile, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a second front, right, and top perspective view of a headrest for automobile, showing the headrest in a state of use.

The broken lines shown in the drawings illustrate portions of the headrest for automobile that form no part of the claimed design, and environment that forms no part of the claimed design.

1 Claim, 9 Drawing Sheets
